UNITED STATES PATENT OFFICE

ERIC A. ENGLIN, OF STILLWATER, MINNESOTA, ASSIGNOR TO J. E. GAGNELIUS,
OF SAME PLACE, AND F. L. ENGLIN, OF OSCEOLA, WISCONSIN.

PERMUTATION-LOCK.

SPECIFICATION forming part of Letters Patent No. 471,498, dated March 22, 1892.

Application filed August 3, 1891. Serial No. 401,617. (Model.)

To all whom it may concern:

Be it known that I, ERIC A. ENGLIN, a citizen of the United States, residing at Stillwater, in the county of Washington and State 5 of Minnesota, have invented certain new and useful Improvements in Permutation-Locks; and I do hereby declare the following to be a full, clear, and exact description of the invention, such as will enable others skilled in the 10 art to which it appertains to make and use the same.

My invention has for its object to provide a permutation-lock which shall be of such simple and cheap construction that it may be 15 employed on trunks, doors, and in other similar uses where key-locks are now employed.

To this end I employ as the principal features of my device a movable locking bolt or plunger, a detent for controlling the same, 20 and a series of independently-movable pieces, which, as shown, are slides provided with notches engageable with the detent. These setting-pieces and their notches are so positioned and related to the engaging portions 25 of the detent that when the notches are moved or assembled into certain predetermined positions relative thereto the detent will be released and permit the locking-bolt to be moved into an unlocked position; but 30 when any of the notches are in any other position the detent will be held and the locking-bolt be secured in a locked position. Both the locking-bolt and setting-pieces are provided with projecting lugs, which extend 35 through slots to the outside of the case, by which they are moved into their different positions. The lugs on the setting-slides are pointed and co-operate with a scale marked or secured on the front face of the lock-case. 40 In other words, the projections and scale constitute an indicator. The registering positions of the notches on the setting-slides with the engaging portion of the detent correspond to the registering positions of the respective 45 indicator fingers or lugs with some predetermined positions on the scale. The combination of positions is preferably set to require an irregular order of manipulation, and the combination may be changed at will. The 50 discovery of this combination by experiment would be practically impossible, as the num-

ber of permutations offered by the notches and different positions in which they may be set are very great.

My invention also comprises other supplementary devices and peculiarities in construction, all of which appear in the following description, and are more particularly pointed out in the claims.

In the accompanying drawings, which show 60 my preferred form as constructed for use for a trunk-lock, like letters refer to like parts throughout the several views. All the views are in perspective.

Figures 1 and 3 are rear views with the rear 65 plate removed, showing the locking-bolt respectively in a locked and an unlocked position. Figs. 2 and 4 are front views, respectively, of Figs. 1 and 3; and Fig. 5 is an inside view of the rear plate removed. Figs. 6, 7, 70 8 and 9 are views of a shield or concealing-cover for the lock. Fig. 9 is a detail of one of the notched setting-slides and its carrier-slide detached, and Fig. 10 is a detail of a setting-slide.

a is the lock-case, provided with a detachable back *a'*.

b is the locking-bolt working through a perforation *a*² in one end of the case and near its inner end between guides *a*³.

c are the notched setting-slides, provided with the notches *c'*, and *d* are carrying-slides, having a block-like head *d'* at one end, to which the setting-slides are detachably secured. Both the carrying-slides and the 85 notched slides work in keepers *a*⁴, cut in the supports *a*⁵, secured, respectively, to the front and rear plates of the lock-case.

f is the detent, pivoted to the case at *f'*, extending under the locking-bolt, then curved 90 upward into the inward path of the plunger, as shown at *f*², and then turned downward and provided with steps *f*³ for engaging the notches *c'* and the setting-slides *c*. The detent is held to work against the inner end of 95 the locking-bolt by a finger *b'*, depending from the locking-bolt *b* and engaging the under side of the detent. In the locked position the engaging steps *f*³ of the detent rest on the upper face of the notched setting-slides, with the upcurved portion *f*² in the 100 inward path of the locking-bolt. When the

notches are all brought to registration with the said steps f^3 , the detent may be forced downward and the locking-bolt moved inward or unlocked. The locking-bolt is moved 5 by the projecting lug or knob b^2 , and the notched setting-slides are moved and their positions indicated on the scale g by the projecting pointer-lugs c^2 .

g' is a retaining-finger engageable with the 10 lugs b^3 and c^2 , after the bolt is locked, for holding them, as shown in Fig. 2. This finger g' is pivoted to the case at g^2 and has a square shaft g^3 , extending into the case, which is engaged by a flat spring g^4 for holding the finger in either of two positions, as shown in 15 Figs. 2 and 4. The notched setting-slides are made interchangeable to permit variation of the combination.

Each setting-slide is provided with a notch 20 on both bottom and top, which permits a change in the combination by turning them over, and the notches are so located that the relative position of the notches may again be changed by reversing them endwise. This 25 arrangement of the notches gives four changes to each slide, and the slides are interchangeable with each other. By providing notches on the four sides of the setting each slide would give eight changes. Comparatively 30 few slides constructed in this way will afford a large number of permutations.

Referring to Figs. 6, 7, and 8, k and l are parallel brackets secured, respectively, over and under the lock. In the bracket k is pivoted 35 and yieldingly mounted a shield or leaf m , having a square shank n , engaged by a flat spring p , which permits a vertical movement of the leaf and also serves to hold it in an open or raised position, as shown in Fig. 8. 40 The bottom of this leaf m is provided with a depending lip m' , which is engageable in a groove l' of bracket l for securing the same in its latched or closed position, as shown in Fig. 6. The shield is also provided with a finger-catch m^2 , by which it may be raised or unlatched, as shown in Fig. 7.

r in Figs. 1 and 3 represents the hasp of the lock secured to the lid of the trunk or other part in position to be engaged by the locking-bolt.

The operation of the parts has already been described.

The advantage of the lock is that it offers the security of a combination-lock at a relatively low price, inasmuch as the parts are 55

simple and cheaply made, thus enabling the use of the same in many places where key-locks would be otherwise used on account of cost.

It will of course be understood that the principle is capable of a diversity of constructions. The lock-bolt and setting-pieces, for example, could be of different shape and the other parts correspondingly modified without departing from the spirit of my invention. 60 65

What I claim, and desire to secure by Letters Patent of the United States, is as follows:

1. The combination, with the lock-case a a' , of the locking-bolt b , the detent f , having the steps f^3 , the carrier-slides d , having head-blocks d' , the projections c^2 , working through slots in the case, and the setting-slides c , having notches c' , detachably connected to the said head-blocks d' on the carrier-blocks d , substantially as described. 70 75

2. The combination, with the lock-case, of the notched setting-slides, the carrier-slides connected thereto and provided with projections working through slots in the case, and the spring-held finger g' for holding the slides, 80 substantially as described. 85

3. A shield for a lock, comprising a bracket k , securable above the part to be protected, a bracket l , secured below the part to be protected and provided with a recess or groove l' , the leaf or plate m , pivoted to the bracket k and provided with the square portion n , and the spring p , seated in the bracket and bearing against the square part of said plate for holding it in its closed or open position, substantially as described. 90

4. The combination, with the slotted lock-case, of the carrier-slide d , having the head-block d' , the projection c^2 of the setting-slide c , having the notches c' , and the guide-blocks a^5 , having the grooves or guideways a^4 for said slides, substantially as described. 95

5. The combination, with the lock-case a a' , having the scale g , of the locking-bolt b , the detent f f' f^2 f^3 , as described, the finger b' , the guide-blocks a^4 a^5 , the carrier-slides d d' , and the notched setting-slides c c' , all arranged and operating substantially as described. 100

In testimony whereof I affix my signature in presence of two witnesses.
